ENGRAVING MACHINE.

No. 415,450.

Patented Nov. 19, 1889.

UNITED STATES PATENT OFFICE.

THEOPHILUS CHARLES EBERHARDT, OF CUERO, TEXAS.

ENGRAVING-MACHINE.

SPECIFICATION forming part of Letters Patent No. 415,450, dated November 19, 1889.

Application filed December 21, 1888. Serial No. 294,296. (No model.)

To all whom it may concern:

Be it known that I, THEOPHILUS CHARLES EBERHARDT, a citizen of the United States, residing at Cuero, in the county of De Witt, 5 and State of Texas, have invented a new and useful Improvement in Engraving-Machines, of which the following is a specification.

My invention relates to an improvement in engraving-machines; and it consists in the 10 peculiar construction and combination of devices that will be more fully set forth hereinafter, and particularly pointed out in the claims.

In the accompanying drawings, Figure 1 15 is a perspective view of an engraving-machine embodying my improvement, the platen being lowered and the machine arranged in position for use. Fig. 2 is a similar view showing the platen raised. Figs. 3, 4, 5, 6, 20 and 7 are detail perspective views.

A represents a rectangular base-board of suitable size, on which is arranged a rectangular plate or table B, the latter being secured to the base A by screws and detachable from the said base. 25

C represents a plate, which is arranged transversely under the table or plate B, near one end of the latter, is fitted between said plate B and the base A, and is provided at 30 its ends with vertical arms D E, which rise from the plate B, and extend through notches or openings in the latter, as shown.

F represents the platen, which has one end pivoted between the upper ends of the arms 35 D by screws G, having conical engaging ends fitting in similarly-shaped sockets in the platen, said screws working in threaded openings in the upper ends of the arms D, and having jam-nuts H, by which they may be secured 40 at any desired adjustment. Screw-studs I are arranged in the outer corners of the platen F, project from the under face thereof, and are adapted to enter sockets K in the upper ends of the arms E when the platen F is turned 45 downward on said arms E to a position parallel with the table or plate B. From the pivotal end of the platen projects an arm L, which is adapted to engage one side of the plate or table B when the platen is turned to its elevated position (shown in Fig. 2) and support 50 the said platen in the said position.

M represents a plate, which is arranged

transversely on the under side of the platen at a suitable distance from the outer end thereof, and has notches or rabbets N in its 55 ends.

O represents a clamp, which is also arranged on the under side of the platen, and is provided at its ends with right-angled arms P, that fit in the rabbets N. From the upper 60 side of the clamp O, at the center of the same, projects a stem R, which extends through a central opening in the platen F, and on the outer end of the said stem is pivoted a lever S, the said lever having a cam T at its inner 65 pivotal end adapted to engage a transverse pin U in the outer end of stem R.

V represents a pair of adjusting-screws, which engage threaded openings near the outer corners of the clamp O, and have their 70 inner ends bearing against the under side of the platen. A pair of spring-arms W have their inner ends secured to the under side of the platen and have their free ends bearing against the upper side of the clamp O, the 75 function of the said spring-arms being to normally move the said clamp O from the platen.

The operation of this portion of my invention is as follows: A plate or other substance 80 to be engraved is placed behind the plate M, with its ends projecting beneath the rabbets N, and by turning the lever S the operator causes the cams T to engage the cross-pin U, and thereby draw outward on the stem R and 85 clamp O, and consequently cause the right-angled arms P of said clamp to bear on those ends of the plate which are over the rabbets N, and thereby clamp the said plate on the plate M. 90

X represents a rectangular plate of suitable size, which is fitted in a countersunk opening in the upper side of plate B and arranged upon the plate C, the said countersunk opening being of sufficient depth to cause the upper side of plate X to be flush with the surface of plate B. 95

Y represents a plate which is arranged on the plate B, and has a frame A' around its edges, which is adapted to retain a paper, 100 slate, or other surface on which a character, drawing, engraving, or other matter to be copied is printed, drawn, or otherwise inscribed.

B' represents a pantograph, which comprises a pair of parallel bars C' D', of unequal lengths, a bar E', which has its ends connected to the said bars, and a bar F' which is connected at and near one end to the outer ends of said bars. The inner end of the bar C' is pivoted on a stud G', that rises from the plate B, near one corner thereof.

H' represents screw-studs which pivot the bars F' to the bars C' D', and pivot the bar E' to the bar C', said studs extending downward and bearing on the plates X and B, and serving to support the pantograph horizontally over said plate and in a plane parallel therewith.

15 The screw-stud I', which connects the bars D' and E', has a threaded socket in its upper end, in which is screwed a stylus or graving or etching point K'.

L' represents a sleeve or knob, which is secured on the bar F' at the outer end thereof, and through which extends a tracing-pencil M', the latter being secured in the knob or sleeve L' at any desired adjustment by a set-screw N'.

25 O' represents an adjusting-screw, which is arranged midway between the arms E, and is adapted to bear under the free ends of the platen F.

The operation of my invention is as follows:

30 When the plate on which the engraving is to be made has been secured to the under side of the platen in the manner before described, the platen is turned down upon the arms E, the studs I entering sockets K in the upper ends of said arms and serving to secure the platen rigidly thereon. The plate X is adjusted vertically in a plane parallel to the plate M by turning the screws Y' to cause the stylus K' to engage equally at every point the 40 surface of the said plate to be engraved, the depth of the cut made by the said stylus being regulated by the screw O'. The original from which the engraving is to be made or the slate or paper upon which any desired word 45 is to be written being secured on the plate Y, the operator, by grasping the knob or sleeve L' and tracing the said original or writing the desired word or symbol with the pencil-point M', causes a reduced fac-simile thereof 50 to be engraved on the plate or engraving-surface, as will be readily understood, the said engraving being in reverse. If it is desired to have the engraving exactly alike the original and not in reverse, it may be accomplished 55 by securing the block, plate, or surface to be engraved on the plate X and reversing the stud I' and stylus K' in such manner as to cause the stylus to bear downward on said block, plate, or surface.

60 This apparatus is especially designed for engraving plates to be used for printing mailing-lists for newspapers and other peri-

odicals, and which form the subject-matter of another application for Letters Patent of the United States, filed by me this day; but 65 the said apparatus may be also employed for other useful purposes, such as engraving on wood, engraving matrices for stereotype-castings from chalk-covered steel-plates, &c.

Having thus described my invention, I 70 claim—

1. The combination of the bed-plate, the downwardly-facing platen mounted thereon, and the pantograph pivoted on the bed-plate and having the tracing-point and the engraving-point or stylus, substantially as described.

2. In an engraving-machine, the platen, in combination with the plate M on the under side thereof, the clamp-plate O, having the stem R extending through the platen, and the lever pivoted on the said stem and having the cam to operate the clamp, substantially as described.

3. In an engraving-machine, the combination, with the platen, of the clamp-plate O on the under side thereof, the springs W to normally move the clamp-plate from the platen, the stem R, projecting from the clamp-plate through an opening in the platen, and the lever pivoted on the said stem and having the cam to operate the clamp, substantially as described.

4. The combination, in an engraving-machine, of the platen having the plate M on its under side with rabbets N, the clamp-plate O, having the right-angled arms P to engage said rabbets, the stem R, projecting from the clamp-plate through the platen, and the lever having the cam engaging the said stem, 90 for the purpose set forth, substantially as described.

5. The combination of the bed-plate C, having the arms or standards D E, the platen F, having one end pivoted between the arms D, 105 and having the studs I to engage sockets K in arms E, and the pantograph pivoted on plate or table B and having the stylus, substantially as described.

6. The combination, in an engraving-machine, of the table B, the bed-plate C, the platen F, the plate X on the former, having the adjusting-screws Y' resting on bed-plate C, and the pantograph having the stylus arranged under the platen F and provided with 115 the depending stud bearing on the plate X, substantially as described.

In testimony that I claim the foregoing as my own I have hereto affixed my signature in presence of two witnesses.

THEOPHILUS CHARLES EBERHARDT.
